DESIGN FOR A WALL LAMP

Emanuel Ostrow, New York, N. Y.

Application April 27, 1937, Serial No. 68,997

Term of patent 3½ years

To all whom it may concern:

Be it known that I, Emanuel Ostrow, a citizen of the United States and a resident of the city of New York (Borough of Bronx), county of Bronx and State of New York, have invented the new, original, and ornamental Design for a Wall Lamp, of which the following is a specification, reference being had to the accompanying drawing, forming part thereof.

The figure is a perspective view of a wall lamp showing my new design.

The opposite side of the lamp is substantially the same as that disclosed in the drawing.

The dominant feature of my design resides in the part shown in solid lines.

I claim:

The ornamental design for a wall lamp, as shown and described.

EMANUEL OSTROW.
